United States Patent Office.

EDWIN REES, OF STODDARTSVILLE, PENNSYLVANIA, ASSIGNOR TO HIMSELF AND LEWIS STULL, OF SAME PLACE.

Letters Patent No. 102,865, dated May 10, 1870.

IMPROVED SCRUBBING-BRUSH AND MOP-WRINGER.

The Schedule referred to in these Letters Patent and making part of the same.

To all whom it may concern:

Be it known that I, EDWIN REES, of Stoddartsville, in the county of Luzerne and State of Pennsylvania, have invented a new and useful Improvement in Combined Scrubbing-Brush, Mop, and Wringer; and I do hereby declare that the following is a full, clear, and exact description thereof, which will enable others skilled in the art to make and use the same, reference being had to the accompanying drawing forming part of this specification.

Figure 1 is a side view of my improved device.

Figure 2 is a top view of the same.

Similar letters of reference indicate corresponding parts.

My invention has for its object to furnish a combined scrubbing-brush, mop, and wringer, which shall be so constructed that the windows, the floors, and other wood-work of the house may be scrubbed, and wiped or mopped, and the mop wrung out, without its being necessary for the operator to stoop or wet her hands; and

It consists in the combined scrubbing-brush, mop, and wringer, constructed and arranged as hereinafter more fully described.

A is a scrubbing-brush, constructed in the ordinary manner, and having a long handle, B, attached to it.

The handle B may be provided with a hand-piece or handle, C, for convenience in bearing down upon or raising the instrument.

To the back of the brush A, near its ends, are attached two short uprights, D, the upper ends of which are connected by a horizontal rod, E. If desired, the rod E and uprights D may be made in one piece and bent twice at right angles to form the uprights.

Upon the rod E is placed a sponge, F, preferably of cylindrical form.

Upon the rod E, at each end of the sponge or mop F, is placed a disk, G, so that the water may be squeezed out of the said sponge F by pressing the said disks G toward each other.

H are two levers, upon the lower ends of which are formed eyes or hooks, which are placed upon the rod E at the outer sides of the disks G.

The levers H cross each other, and are pivoted at their point of intersection to the middle part of the handle B, and their free ends or handles extend up nearly to the end of the handle B.

By this construction, by pressing the free ends of the levers H toward each other, the sponge F will be compressed and the water squeezed out.

By this construction, the floor or other surface may be scrubbed with the brush A, wiped or washed with the sponge F, and the water squeezed out of the said sponge, without its being necessary for the operator to stoop or wet her hands.

Having thus described my invention,

I claim as new and desire to secure by Letters Patent—

The combination of the uprights D and rods E, whether made in one or more pieces, the sponge F, disks G, and levers H, with each other and with the brush A and long handle B, substantially as herein shown and described, and for the purpose set forth.

EDWIN REES.
